DESIGN FOR A DRESS ENSEMBLE

Rae Wein, New York, N. Y., assignor to Isaac Edward Levine and Joseph Henry Levine, doing business as Lewis Levine & Sons, Cincinnati, Ohio

Application July 6, 1938, Serial No. 78,288

Term of patent 3½ years

To all whom it may concern:

Be it known that I, Rae Wein, a citizen of the United States and a resident of the city of New York, in the county of New York and State of New York, whose post office address is 838 West End Avenue, city and State of New York, have invented a new, original, and ornamental Design for a Dress Ensemble, of which the following is a specification, reference being had to the accompanying drawing, constituting a part thereof.

Fig. 1 is a front view of a dress ensemble showing my design.

Fig. 2 is a rear view thereof.

Fig. 3 is a front view of the dress section of the ensemble shown in Fig. 1.

Fig. 4 is a rear view of Fig. 3.

The characteristic feature of my design resides in the combination on the ensemble disclosed of the specific button trimmed pockets arranged on the jacket member as shown, each button covering an area equal to one-fourth of the pocket size and being centrally disposed thereon, said buttons matching those on the blouse front.

I claim:

The ornamental design for a dress ensemble, substantially as shown and described.

RAE WEIN.
